United States Patent Office.

JACOB F. SHARP, OF WILMINGTON, DELAWARE.

Letters Patent No. 87,880, dated March 16, 1869.

IMPROVED OIL-BOX FOR CAR-AXLES.

The Schedule referred to in these Letters Patent and making part of the same.

To all whom it may concern:

Be it known that I, JACOB F. SHARP, of the city of Wilmington, in the county of New Castle, and State of Delaware, have invented a new and useful Improvement on Oil-Box Lids, for oiling and packing journals of car-axles; and I do hereby declare that the following is a full, clear, and exact description of the construction and operation of the same, reference being had to the annexed drawings, making a part of this specification, in which—

Figure 1 is a front view, and

Figure 2, a section through the centre of the lid.

A is the slide.

b, the spring for holding it in place.

The nature of my invention consists in providing the lids of oil-boxes, for oiling and packing journals of car-axles, with a spring-slide, or gate, so constructed as to permit the journals to be packed and oiled without removing the lid, thereby obviating the necessity of removing the face, or lid of the oil-box, by the old and tedious process of unscrewing it.

I construct my oil-box lid in any of the known forms, but in order to obviate the necessity of removing the face of the box, in order to oil or pack the journals, I

make an opening in the centre of the lid, and in this set a slide, or gate, shown at *a*, with a spring, shown at *b*, for keeping it in place.

When the journals of the car-axle require packing or oiling, by applying an upward pressure, or force to the spring *b*, the slide, or gate, is opened, so as to fully expose the journals, ready for oiling or repacking, and this can be done in an instant, whereas, by the old method, a wrench must be used, consuming some time in unscrewing two bolts, to free the lid, or plate.

I do not claim the lid, or box-plate; but

What I claim as my invention, and desire to secure by Letters Patent, is—

A removable car-axle-box cover, having an opening therein, closed at pleasure by a vertically-sliding lid, with projecting handle at top, fastened, when closed, by a centrally-located spring, and having a stop to prevent its entire withdrawal from the cover, all constructed and arranged substantially as and for the purpose set forth.

JACOB F. SHARP.
